SAND TOY

Oscar Fisher, Locust Valley, N. Y.

Application May 25, 1944, Serial No. 537,362

9 Claims. (Cl. 46—41)

1

This invention relates to mechanical toys and more particularly to a gravity operated device of the sand toy type.

It is an object of the invention to provide an improved gravity actuated sand toy that will continue in automatic operation as long as sand or other freely flowing granular material is supplied.

Another object is to provide a simple, sturdy construction which may be made from relatively inexpensive and freely available materials such as certain types of plywood, wood, and various types of molded or shaped non-metallic materials.

Another object is to provide a device of this character which may be shipped in knocked down, compact form and then assembled without the use of nails or the like into a complete operative structure.

Another object is to provide a device of the character specified consisting essentially of flat material and advantageously of such material of a uniform thickness dimension.

Still another object and feature of the invention resides in the application to a device of the type described of the method of assembly which involves securing rectangular strips of a relatively stiff material into an interlocking and mutually supporting relationship by means of complementary recesses or slots adjusted as to dimension as to insure close, more or less force fit of edge portions of one strip with the slot portion of the strip to be connected thereto.

Still another object is to provide in a device of the character described a novel arrangement of the pivotal support for the reciprocating, bucket-carrying lever arms with respect to the supporting frame of the hopper which insures a low center of gravity for the structure and at the same time permits of the use of relatively extended lever arms, thus assuring that the sand can be discharged into a container or into piles spaced from the supporting framework and making it easy to tidy up about the device after it has been used.

A still further object is to provide in a device of the character described a novel and advantageous supporting structure for the sand hopper and the oscillating lever arms associated therewith.

A still further object is to provide in a device of this character an improved hopper construction having at the opposite ends thereof discharge chutes and improved means for controlling flow therefrom.

A further object is to provide in a device of the

2

character described an improved arrangement and means for operating the buckets and controlling discharge therefrom so as to regulate and limit the momentum of the buckets and their associated lever arms as they approach the limit of their outward movement in the discharging part of their cycle of movement.

Other objects, features and advantages will appear upon consideration of the following description and of the drawings, in which:

Fig. 1 is a perspective view illustrating one embodiment of the invention;

Fig. 2 is a sectional view taken on the line 2—2 of Fig. 1 with certain details shown in modified form;

Fig. 3 is an exploded view of the parts of the hopper proper and the top of the standards;

Fig. 4 is a detail view of the arrangement for connecting the levers 14 in fixed angular relation to one another, and

Fig. 5 is a perspective view of a modified form of the pair of levers of the invention with parts broken away.

Referring to the drawings, there is a supporting frame including uprights or standards 10 supporting a hopper 11 provided with chutes 12 at opposite ends which alternately supply sand or other free flowing granular material such as shot, marbles, to buckets 13 pivotally mounted on pins 13a carried by the laterally spaced arms of two levers 14 which are pivotally mounted in fixed angular relation to each other adjacent the base of uprights 10.

As illustrated, the levers 14 are provided at their lower ends with aligned openings which receive with a tight fit a shaft 15 mounted in openings in side members 16 of the base so as to permit angular movement of the shaft. As shown more clearly in Fig. 4, the fixed angular relation of the lever arms 14 is insured by the locking and spacing member 14a which has its end portions 14b fitted into inclined slots 14c adjacent the lower ends of the lever arms 14. It will be understood that these slots are so inclined as to

insure the desired angular relation between the two levers. The intermediate portion 14d of the member 14a depends between the inner sides of the innermost arms of the two levers and acts as a spacer.

Instead of forming the levers 14 of four separate arms and securing them in fixed angular relation to one another, it will be understood that the two levers may be formed, as shown in Fig. 5, by associating two elbow shaped members, each taking the general form of a complementary

pair of the four arms constituting the pair of levers 14 shown in Fig. 4. When two such elbow shaped members are used it will be understood that the member 14a will act as a brace and as a spacer to retain the two members in the desired laterally spaced relation. This modification of the lever arm structure is advantageous when the material employed is of such character that it is susceptible of being stamped out from sheet form or of being molded and at the same time possesses substantially the same resistance to flexure in any direction in the plane defined by the lateral surfaces thereof. Examples of such materials are sheet metals, many molded plastics and various compressed fibrous materials, as well as certain specially laminated plywoods.

As shown, each bucket 13 has parallel triangular sides 13b pivoted at 13a to the adjacent arms of its lever 14 and ends 13c converging toward the bottom of the bucket, thus providing a long open mouth to receive sand or the like from the corresponding chute 12. The pivot 13a is near the top edge of the bucket and eccentrically disposed with respect to the length thereof so as to increase the turning moment required to rotate the bucket to dumping position. At their outer ends the adjacent arms of each lever 14 are connected by a crossbar 17 having, in the embodiment shown, a curved edge facing the hopper 11 which promotes centering of the lever arms and the bucket carried thereby with respect to the corresponding chute 12. The opposite edge of the crossbar is recessed or notched to cooperate with recesses in said arms. Such recesses have substantially parallel sides and are just wide enough to permit the crossbars to be forced into them. This assures a stiff connection while permitting easy assembly and separation. This principle of providing close forced fits of one member into the complementary recess of another is applied consistently throughout in assembling the elements of the device together except where other means is specifically mentioned or implied.

In continuing the assembly of the frame after the ends of shaft 15 have been passed through the openings in side members 16 of the supporting base, the uprights 10 are connected by an upper cross member or bar 20 preferably by forming complementary recesses or slots in both uprights 10 and the bar 20 halfway across and forcing them together. An intermediate crossbar 21 having a similar recessed connection with uprights 10 is also provided. Bars 20 and 21 preferably have both recesses at one edge in which case the complementary recesses in the uprights 10 will be on the opposite side when the bars and uprights are assembled. However, the recesses in each bar 20 or 21 may be on opposite sides, but in this case it is preferable to so assemble the bars 20 and 21 with the uprights 10 as to insure that the recesses at the adjacent ends of the bars 20 and 21 will be in alignment, thus permitting their assembly with an upright carrying both of its complementary recesses on the same side.

The uprights 10 are also shown as provided with recesses 22 at their lower ends for receiving the ends of shaft 15. These recesses are sufficiently wide and deep to permit the shaft 15 to be rotated freely about its axis. The uprights are held in position by inclined braces 23 extending between the crossbar 21 and the vertically inclined crossbars 24, which form with the

side members 16 a supporting base structure. The upper ends of the braces 23 are mitered to engage in a vertical line and are recessed adjacent their opposed vertical faces to cooperate with recesses in the side edges of bar 21. At their lower ends the braces 23 may be miter cut so that their lower edges will be in substantially the same plane as the lower edges of base members 16 and 24. The members 16 and 24 are secured in proper relative positions by means of the complementary recesses 16a and 24a (Fig. 1). The braces 23 are recessed adjacent their lower ends and interfit into corresponding recesses on the lower edges of the members 24 as shown at 24b (Fig. 2).

As illustrated, the hopper 11 comprises parallel sides 25 fitting between the uprights 10 and resting on crossbar 20. The hopper is closed at the ends by downwardly converging end members 26. The sides 25 and ends 26 may be assembled and held together by means of recesses or slots 27 in ends 26 and the complementary downwardly converging recesses or slots 28 in the sides 25, the inclination of slots 28 determining the inclination of ends 26. It will be understood that the positions of the slots 27 and 28 may be reversed as compared with the showing in the drawings; that is, the sides 25 may be slotted from their upper edges downwardly, in which case the slots in the ends 26 will extend from the lower edges of these members upwardly.

Each end 26 of the hopper is provided with an opening 29 through which sand or the like is discharged from the hopper into the corresponding chute 12. The sand is directed toward said openings 29 by inclined bottom members 30 of which the upper ends or edges meet midway between the ends of the hopper and the lower edges engage the ends 26 just below the openings 29 so that the upper surfaces of the bottom members 30 will be flush with the lower sides of openings 29 and, as will be brought out more clearly hereinafter, flush with the upper surfaces of bottoms 31 of chutes 12. The bottom members 30 are shown as supported and held in fixed relation to the hopper sides 25 by grooves 30a in the sides 25 receiving the side edges of the members 30.

Above the hopper is a crossbar 32 provided at its lower edge with slots 33 so spaced as to receive the upper edges of the sides 25 and thus stiffen the sides against lateral pressure and hold them in definite spaced relation at the central portion of the hopper formed thereby. As shown the upper edges of the sides 25 are provided with complementary slots 34 to receive the edge portions of the crossbar 32 adjacent the bottom of the slots therein. As shown in Fig. 3, the uprights 10 are provided with slots 35 to receive the crossbar 32 and thus cooperate with the crossbar to hold the hopper structure against bodily endwise movement. As a modification (see Figs. 2 and 3), the sides 25 may be provided at their bottom edges with shallow cutaway portions or slots 34a to receive crossbar 20, thus providing an alternative or supplemental means for anchoring the hopper against endwise movement.

Each chute 12 may comprise sides 36 with the bottom 34 attached thereto in any suitable manner or the bottom may be formed integrally therewith. Advantageously and as shown, the sides may be provided with hook portions 37 which, when the inner end of the chute is inserted into opening 29 of one of the hoppers

5

and the chute swung down, will engage the inner surface of the adjacent end wall 26 and hold the chute in position. With the parts in this position, the upper surface of the chute bottom 31 will be flush with the bottom of the opening 29 and the inner end of the bottom member 31 will be in abutting relation to the end wall 26 beneath the opening 29.

The chute bottom 31 is necessarily inclined downwardly at a suitable angle and of course the lower edges of the sides 36 have the same inclination. However, the upper edges of the sides 36 diverge upwardly from the lower edges and are shown as nearly horizontal when the chute is in place. This insures a greater capacity near the outer ends of the chutes and avoids a tendency to overflow, at the same time providing better facilities for mounting thereon a control gate 38 pivoted at 39. To assist further in preventing overflow of the chute, a cover piece 39a may be positioned over the top of the chute. As shown there is mounted in the discharge end of each chute 12 a barrier 40 provided at its base with an opening 41 to limit the flow to the gate 38.

For operation thereof each gate is provided with an upwardly extending arm 42 on the upper end of which a member 43 is rigidly mounted by means of cooperative recesses or slots in the two parts. The member 43 at each side of the device has at its outer end a downwardly curved finger 43a adapted to be engaged by the cross piece 17 carried by the corresponding arms of elbow levers 14, when these arms are swung toward the hopper in the operation of the device. The impact of cross piece 17 on the finger 43a causes the arm 42 to swing inwardly at the same time opening gate 38. At the inside of arm 42, the member 43 is provided with a hammer head extension 43b which strikes the adjacent hopper end 26 to limit the opening of the gate 38 and at the same time vibrate the hopper to loosen sand and facilitate its feeding to the chute.

As indicated in Figs. 1 and 2, the left hand bucket 13 is in position beneath the left hand chute 12 and the gate 38 (not visible in Fig. 1) has been opened and the bucket is receiving sand from the hopper. At the right of Figs. 1 and 2, the other bucket 13 is held in tilted position for discharge by means of a flexible connector 44 attached to the bottom edge of the bucket and to a fastener, such as a screw eye secured in crossbar 20.

As soon as enough sand has collected in the left hand bucket 13 to overbalance the right hand bucket and the parts supporting the same, the left hand bucket will move downwardly by action of gravity and raise the right hand bucket into position for filling from the right hand chute 12. As the left hand bucket moves away from the hopper, the member 42, being sufficiently weighted by the member 43 carried thereby, swings outwardly thus swinging the gate 38 to closed position. As the left hand bucket 13 approaches its lowermost position, it will be tilted for emptying by means of flexible connector 44 connected to the bottom thereof. These operations will continue automatically as long as sand is supplied to the hopper. Preferably, sand boxes (not shown) are provided at opposite ends of the apparatus to receive the dumped sand. It should be noted that as a loaded bucket 13 approaches the limit of its downward movement, the corresponding flexible connector 44 will be

6

drawn taut and the bucket turned into dumping position. This turning of the bucket tends to check the velocity of the levers 14 and the dumping of the sand from the bucket as it is turned further lessens the momentum of the lever and its bucket. The combined effect is to reduce substantially the force of the blow struck by the crossbar 17 carried by the arms of the lever 14 at the other end of the apparatus against member 43 and through this member against the adjacent end of the hopper.

As previously indicated, the device may be made from a wide variety of materials that are available in strip or sheet form or lend themselves readily to fabrication into stiff strips, plates or sheets. A material that is particularly suitable for use under present conditions, when metals are practically unobtainable for such purposes, is plywood. Plywood has this further to commend it, that it is relatively inexpensive, light, easy to work, relatively strong and capable of being used to form the structural elements without danger of splitting, as would more likely be the case when certain loosely grained woods are used.

It will be understood that various modifications of the details of the construction and of the arrangements for interfitting the members into supporting and interlocking relationships may be made without departing from the spirit and scope of the invention, which is not to be deemed as limited otherwise than indicated by the language of the appended claims.

I claim:

1. In a toy of the class described, a supporting base having portions adapted to establish an extended area of support with a plane surface, a pair of laterally spaced uprights extending upward from said base and supporting a sand hopper adjacent their upper ends, bracing means extending between said uprights in spaced relation to said supporting base and holding said uprights against lateral displacement with relation to said supporting base, and a pair of angularly related levers each having a length approximating the height of the hopper above said base and mounted for oscillating movement between sand loading and dumping positions about a pivot point disposed in line with said uprights beneath said hopper and closely adjacent said base.

2. In a continuously operable gravity actuated sand toy, a supporting base having portions establishing an extended area of contact with a supporting surface, a hopper supported in elevated relation to and centrally of said base, a pair of angularly related substantially balanced levers each having a length approximating the height of the hopper above said base and pivotally mounted on a pivot positioned adjacent said base for oscillating movement between sand loading positions adjacent said hopper and dumping positions outside the area defined by said supporting base, buckets carried by said levers adjacent the free ends thereof, and means associated with said hopper and actuatable in response to movement of one of said levers to loading position to establish flow of sand from said hopper to the bucket carried thereby and acting automatically to cut off flow of sand from said hopper to said bucket upon movement of said lever away from loading position.

3. In a toy of the class described, a supporting base, a hopper supported in elevated relation to and centrally of said base, discharge chutes on opposite sides of said hopper, pivotally mounted counterweighted gates for controlling flow of sand

from said chutes, the counterweights being attached to said gates above the pivot points thereof, a pair of angularly related levers pivotally mounted on a common pivot adjacent said base for oscillating movement and each carrying a bucket adjacent its free end, said levers being so related to one another and to said chutes that movement of one of said levers bringing its loaded bucket to dumping position will cause the bucket carried by the other lever to be brought to loading position, and means associated with each of said levers for acting upon the counterweight of the gate corresponding thereto when said lever moves to loading position to hold said counterweight to prevent closing movement of the gate, and releasing said counterweight for automatic closing of said gate when the lever moves the bucket away from loading position.

4. In a toy of the class described, an elevated hopper having a discharge chute adjacent one end thereof, a gate pivotally mounted on said chute for controlling the discharge of sand therethrough, said gate having an arm extending upwardly from said pivot and carrying a counterweight normally urging said gate to closed position, said counterweight having an outwardly extending portion adapted to receive the impact of a tripping member and an inwardly extending hammer portion adapted to transmit impacts to the end of said hopper when said upwardly extending arm is moved inwardly in response to impacts applied to said outwardly extending portion.

5. In a toy of the class described, a supporting base having portions adapted to establish an extended area of support with a plane surface, a hopper supported in elevated relation to and centrally of said base, a pair of angularly related levers mounted for oscillating movement between sand loading and dumping positions about a pivot point disposed adjacent said base, said levers each carrying a bucket and means controlling flow of sand from said hopper to said buckets when in loading position, and means concomitantly acting on both levers to lessen the momentum of the levers as they approach the limits of their oscillatory movements.

6. In a toy of the class described, a supporting base having portions adapted to establish an extended area of support with a plane surface, a hopper supported in elevated relation to and centrally of said base, a pair of angularly related levers mounted for oscillating movement between sand loading and dumping positions about a pivot point disposed adjacent said base, said levers adjacent the ends thereof opposite to said pivot point each carrying a pivoted bucket and means controlling flow of sand from said hopper to said buckets when in loading position, flexible means connecting said buckets with a stationary part of said structure, said flexible means serving

to tilt said buckets as they approach dumping position, and means acting at the bucket-carrying ends of said levers and cooperating with said controlling means when said buckets approach loading position to retard the movement of said levers.

7. In a toy of the class described, means supporting a hopper in elevated position, a pair of angularly related levers pivotally mounted for oscillation about a central pivot disposed beneath said hopper, said levers each carrying a bucket and each being adapted to bring its bucket to sand loading position beneath the hopper at one extreme of its movement and to move its bucket to dumping position at the opposite extreme of its movement, and means concomitantly acting on both of said levers to lessen the momentum of the levers as they approach the limits of their oscillatory movements.

8. In a toy of the class described, means supporting a hopper in elevated position, a pair of angularly related levers pivotally mounted for oscillation about a central pivot disposed beneath said hopper, said levers each carrying a bucket and each being adapted to bring its bucket to sand loading position beneath the hopper at one extreme of its movement and to move its bucket to dumping position at the opposite extreme of its movement, and means acting on each lever and effective as each lever approaches the limits, respectively, of its movement to dumping position and to loading position to apply a braking action on said lever.

9. In a toy of the class described, means supporting a hopper in elevated position, a pair of angularly related levers pivotally mounted for oscillation about a central pivot disposed beneath said hopper, said levers each carrying a bucket and each being adapted to bring its bucket to sand loading position beneath the hopper at one extreme of its movement and to move its bucket to dumping position at the opposite extreme of its movement, flexible means connecting said buckets with a stationary part of said structure, said flexible means serving to tilt said buckets as they approach dumping position, and means acting adjacent the ends of said levers opposite to said pivot for retarding the movement of said levers as said buckets approach loading position.

OSCAR FISHER.
